ARRANGEMENT FOR AVOIDING DOUBLE PULL-OFFS IN SYSTEMS SERVING SINGLING-OUT OF FLAT ARTICLES

Fritz Buchwald, Thalaiweg, Germany, assignor to International Standard Electric Corporation, New York, N.Y., a corporation of Delaware

Filed May 1, 1962, Ser. No. 191,593

Claims priority, application Germany, May 2, 1961, St 17,768

7 Claims. (Cl. 271—26)

This invention relates to document sorting systems and more particularly to an arrangement for avoiding double pull-offs in systems requiring the singling-out of flat articles.

The singling-out of piled articles plays an important role in mechanizing and automatizing the handling of documents. Especially with respect to the feeding-in of thin documents, such as checks or bills to accounting machines, special care has to be taken that the documents are individually fed to a conveying system with a constant minimum spacing, before being fed to the processing positions or machines. If, due to a double pull-off, two documents are conveyed simultaneously, it is likely they will be recognized by the processing machine as one single document, so that one of these documents will be completely skipped in processing. Such an error, if detected, would call for a checking of all of the already processed documents, thus making it very doubtful whether the whole system is economical. For this reason arrangements have to be provided for reliably preventing such a double or multiple pull-off. In addition thereto it is still required that such an arrangement must not only be capable of operating with a high accuracy, but also at a high speed. Thus, for example, 30 and more documents must be capable of being singled out per second with a practically constant spacing between them, without causing a double or multiple pull-off.

Since also documents of a thin material, such as of a low-resistance paper, have to be processed, a careful handling of the documents must be safeguarded by the singling-out arrangement.

With respect to the above mentioned machines it is a further requirement that the supply of the documents must be capable of being randomly interrupted, and continued thereafter.

It is the object of the present invention to provide an arrangement meeting the above mentioned requirements. One of the features of this invention is the use of opposing forces of suction of unequal force to effect a separation of piled up articles.

This invention relates to an arrangement adapted to reliably avoid a double or multiple pull-off in a preferably pneumatic type of system serving the separation (pull-off) of piled flat and thin articles such as documents made of thin paper, wherein the pulled-off articles are conveyed by an apertured belt which is led over the openings of a source of suction air. The invention consists in that in the conveying direction, beyond the pull-off device, and at the two opposite sides of the conveying channel, there are arranged the outlets of a source of suction air, of which those on the side of the perforated conveyor belt are provided with the larger suction holes, and thus have the greater suction force, while those on the opposite side are arranged in the conveying direction in front of the first mentioned openings, and are thus spaced apart the conveyor belt by a distance corresponding to some thicknesses of the material of the articles to be conveyed. This spacing is in the order of about one or more millimeters. The sucking-off airducts of both groups of outlets are assembled in one common pipe and are throttled sharply

2

in such a way that an underpressure can only build itself up with the pipe system when the large-diameter outlets on the side of the conveyor belt are throttled by the articles to be conveyed.

5 The invention will now be explained with reference to the accompanying drawings, in which:

FIG. 1 is a perspective view of an arrangement in accordance with my invention;

10 FIG. 2 is a schematic view of the arrangement shown in FIGURE 1.

The piled articles to be singled-out or separated, i.e. a pile of equisized checks or other documents, are contained in a receiving device 1. With a constant pressure this pile of articles is pressed by the action of a not shown device, against the conveying plane, so that the front article will come to lie against the belt 6. This conveyor belt 6, in turn, is led over a surface on which there are arranged the outlets 2 and 3 of a source of suction air. Suction is effected at 2 and 3 via tubes 2a and 3a. Valve 20 V₁ controls the suction to outlets 3. The outlets 3 are arranged in the central portion of the surface, and have a high suction force. The outlets 2 have a smaller suction force, and are arranged at the margins of the surface. The belt 6 is provided with perforations 6a, being in 25 agreement with the outlets 3, for performing the sucking-on of one of the documents and for taking it along.

The belt 6 covers only the central portion of the surface occupied by the outlets 3, so that the outlets 2 remain uncovered. The side of the receiving device 1 lying in the 30 conveying direction, may be formed either by a limit stop, a roller, or a retaining device 5 extending so far to the conveyor belt, that there will only remain a small gap for pulling off the conveyed articles. Reference numeral 4 indicates the blowing nozzles, the purpose of which will 35 be explained hereinafter in connection with describing the mode of operation of the system.

To the short pipe pieces 2a and 3a there are connected the sources of suction air, and to the short pipe piece 4a which supplies 40 4 with air there is connected a source of compressed air. Along the conveying path, and behind the pull-off device, there is provided an arrangement 7 in accordance with my invention for avoiding a double or multiple pull-off. This arrangement 7 likewise consists 45 of a surface over which the perforated conveyor belt is led, which is provided with suction-air nozzles, and furthermore of another arrangement of suction-air nozzles which, together with the aforementioned surface, forms the second opposite side of a conveying channel, and likewise contains suction-air nozzles. In the common airduct 50 of both nozzles there is arranged a throttle valve B which is shown in FIG. 2.

In order to ensure a minimum spacing between the individual separated articles, the singling-out device is operated by the article to be conveyed with the aid of photo-cells. Thus, for example, there may be provided four 55 light barriers 10, 11, 12 and 13, of which the sources of light are arranged on the one side, and the receivers on the other side of the conveying channel. Further suction-air nozzles 8 and 9 are disposed behind the arrangement 60 7 on a surface, over which the conveyor belt 6 is moved. When a document has passed through 7 the valve V₂ is closed causing suction to go through tubes 8a and 9a to outlets 8 and 9 for conveying the document further along the system. For the purpose of improving the pull-off 65 operation, it is known to bend the first object of a pile, for increasing the rigidity of the article, and making it more suitable for being transported. For this reason the surface is appropriately bent in such a way that upon sucking-on of the first article to be conveyed, this article 70 will likewise be bent. This is effected by the suction-air nozzles 2 with the assistance of the blowing-air nozzles 4.

The conveyor belt is of a width which does not cover up the suction-air nozzles 2 or 3 respectively, and therefore need only be bent slightly or not at all. In order that the article to be conveyed is retained close to the belt 6, and is conveyed in opposition to the holding effect of the nozzles 2, the suction effect of the nozzles 3 must be substantially stronger than that of the nozzles 2. Behind the pull-off device the bending of the articles to be conveyed is maintained with the aid of guides (not shown). The nozzles 3, on one hand, and 3, 7, 9, on the other hand, are alternately applied to a source of suction air via a quick-acting valve V_0 . By reversing this valve the system may be randomly switched to cause either the transporting or the stopping.

The arrangement shown in the drawings operates as follows: First of all the receiving device 1 is provided with a pile of aligned documents resting on one hand, on the base plate of the supporting device and, on the other hand, against the limit stop or retaining plate 5. The front piece of the piling device (stacking device) is applied with its central portion to the bolt 6 moving in the conveying direction, whereas its two marginal-strip portions are loosened by the action of the blowing-air nozzles 4, and sucked-on by the stationary nozzles 2, thus being bent about an axis extending in the conveying direction. When an article is supposed to be conveyed then a vacuum is applied to the nozzles 3, so that the article is sucked so strongly against the belt 6 that it, in opposition to the retaining force of the fixed nozzles 2, is taken along by the belt until its front end, between the opposite walls of the device 7, will darken the light barrier 10. On account of this valve V_1 will disconnect the vacuum from the nozzles 3, so that a conveyance is no longer performed from this end. After having passed the conveying nozzles F of the device 7 a strong vacuum is permitted to be built up in the strongly throttled boxes 7a which are connected to the air supply, thus performing the further conveyance of the article. At the same time this vacuum appears on the opposite side of the article to be conveyed, namely at the retaining nozzles H, so that the article will be retained. The relationship between the nozzles F and H is such that the conveyance is continued in opposition to the retaining force of H. However, if together with the first article to be conveyed, a second one has been taken along accidentally as well, then this second article will be retained by the holding nozzles until either the passing article to be conveyed has released the light barrier 10, or until the subsequently arranged light barriers perform the call-up of further articles.

In the course of the further conveying process first of all the light barrier 11 and thereupon the light barrier 12 is darkened. The light barrier 12 is arranged at a point where the conveying article is taken over by a further group of suction-air nozzles 9. Here the article itself shuts off the nozzles of the device 7 for interrupting the supply int his way. After the rear edge of the article to be conveyed has passed the light barrier 11, the device 7 is switched-on to become effective again. In this way, between the individual articles to be conveyed, there is established a spacing corresponding to the spacing between the light barriers 10 and 11. In addition thereto the light barriers 11, 12, and 11, 13 may also be used to perform a space- and length-control in this manner.

If, for some reason or other, the conveying operation is supposed to be stopped, then the vacuum is switched-off from the conveying nozzles 3, 7 and 9 by the main valve V_0 , and is applied to the retaining nozzles 3. In this way it is possible to perform a random stopping and re-starting of the conveying operation.

While I have described the principles of my invention in connection with specific apparatus, it is to be clearly understood that this description is made only by way of example and not as a limitation to the scope of my invention as set forth in the accompanying claims.

What is claimed is:

1. Arrangement for singling out and conveying flat, thin articles, from a stack of such articles comprising: a perforated belt; guide means for causing said belt to follow a predetermined path in an edgewise position; means for holding a stack of such articles adjacent said path; compressed air means having outlets adjacent said stack and directed thereto to separate a foremost article, in said stack of said articles, from said stack; first suction means adjacent said belt on the side opposite said stack with a given suction power which cooperates with said belt to convey said articles; second suction means, with less suction power than said given power, disposed on the other side of said stack opposite said first suction means to draw and hold thereto any adjacent article overlapping and conveyed with said foremost article; and control means, including sensing means positioned along said path to control said first suction means and space said articles, to cooperate with said belt and said first suction means to subsequently convey said any adjacent article, and to start and stop operation of said arrangement.

2. Arrangement for singling out and conveying flat, thin articles from a stack of such articles comprising:

a perforated belt; guide means to direct said belt along a predetermined path in an edgewise position; means for holding a stack of such articles adjacent said path; compressed air means having outlets adjacent said stack and directed thereto to separate a foremost article, in said stack of said articles, from said stack; first suction means adjacent said belt on the side opposite said stack with a set suction power which cooperates with said belt to convey said articles; second suction means, with less suction power than said set suction power, disposed along said path adjacent said stack to bend said foremost article away from said stack; third suction means, with less suction power than said set suction power, disposed on the other side of said stack opposite said first suction means, to draw and hold thereto any adjacent article overlapping and conveyed with said foremost article; and control means, including sensing means positioned along said path to control said first suction means and space said articles, to cooperate with said belt and said first suction means to subsequently convey said any adjacent article, and to start and stop operation of said arrangement.

3. Arrangement for singling out and conveying flat, thin articles, comprising:

compressed air means having at least one output directed towards said articles to separate a foremost article to be conveyed; conveying means adjacent said articles, including a perforated belt, and first suction means behind said belt with a given suction power for pulling the articles to the belt bending means, including second suction means adjacent said foremost article and said belt with less suction power than said given suction power, and guiding means adjacent said foremost article, wherein both said suction means cooperate to bend said article away from any adjacent article overlapping therewith; holding means, including third suction means positioned along said belt on the side opposite said first suction means with less suction power than said given suction power to hold said any adjacent article to prevent overlapping conveyance thereof with said foremost article; and

control means, including sensing means positioned along said path to control said first suction means and space said articles, to cooperate with said conveying means to subsequently convey said any adjacent article, and to start and stop operation of said arrangement.

4. Arrangement for singling out and conveying flat, thin articles, comprising:

- a perforated belt;
- guide means for causing said belt to follow a predetermined path in an edgewise position;
- a plurality of compressed air outlets arrayed along and directed across said path to separate a foremost article in a stack of said articles from said stack;
- a first plurality of suction outlets arrayed in the center of said path, over which said belt passes;
- a second plurality of suction outlets arrayed along said path, interposed between said plurality of compressed air outlets and said first plurality of suction outlets;
- a third plurality of suction outlets arrayed in the center of said path, disposed a distance along said path from said first plurality;
- a fourth plurality of suction outlets arrayed in a plane opposite to said third plurality, wherein said belt passes therebetween;
- a fifth plurality of suction outlets arrayed in the center of said path, disposed a distance along said path from said third plurality;
- two lengthwise arrays of suction outlets, one above and one below said fifth plurality, extending along said path;
- said first, third, and fifth pluralities cooperating with said belt to convey said foremost article along said path;
- said second plurality causing said foremost article to be bent away from said stack;
- said fourth plurality causing any adjacent article, overlapping said foremost article to adhere thereto; and
- control means to space said articles, to cooperate with said belt and with said third and fifth pluralities to subsequently convey said any adjacent article, to start and stop operation of said arrangement, and to cooperate with said lengthwise arrays wherein said arrays hold any article thereat during halt.

5. Apparatus for singling out flat thin articles and conveying the articles comprising: a perforated belt; guide means for causing said belt to follow a predetermined

path in an edgewise position; a first group of suction outlets on one side of said path which cooperate with said belt; a second group of suction outlets on the other side of said path disposed opposite to said first group, said second outlets being smaller than said first outlets; a common source of suction air for both sets of outlets so that a single article will be drawn to said belt and conveyed by it and an adjacent article overlapping therewith will be drawn to said second group of outlets and held by said second group; and, control means for causing said adjacent article to be conveyed along said path by said belt a predetermined distance behind said single article, said guide means comprising means for causing said belt to be guided over a surface which is concave in relation to said belt, the axis of said concavity being parallel with said path.

6. Apparatus according to claim 5 wherein the concave surface on which the perforated conveyor belt is guided, is provided with suction-air outlets in its central portion and in its marginal-strip portions.

7. Apparatus according to claim 6 wherein

- said perforated conveyor belt traverses the surface of said central portion, placing the perforations in said belt in registry with said suction-air outlets of said central portion, said registry thereby configuring a given suction-air area with a given suction force; and
- said suction-air outlets in said marginal-strip portion form a suction-air area which is smaller than said given area, having less suction force than said given suction force.
